TEXTILE MACHINERY

Arthur Richter, Chemnitz, Germany

Application November 27, 1933, Serial No. 699,984
In Germany December 5, 1932

6 Claims. (Cl. 66—1)

This invention relates to textile machinery, and particularly to flat hosiery frames.

As a matter of experience, in flat hosiery frames the narrowing rods for the narrowing, lace or other motions cause much trouble if subjected to great variations in temperature, which is due to the fact that, owing to their form, these rods undergo a change in length during temperature variations, which differs from that of the needle bars, sinker heads and other parts that cooperate with them. In order to overcome these difficulties it has been the general practice hitherto to make changes in the construction of the machine, e. g. by subdividing the narrowing rods or by resorting to similar makeshifts, which involved considerable expense and interfered with the clear arrangement of the machine. For example, the subdivision of the narrowing rods requires for every subdivided part special adjusting means, even if the rod portions are controlled merely by auxiliary adjusting devices fully governed by the pattern mechanism.

The construction according to the invention differs fundamentally from known designs in so far as the narrowing rods for instance are fully protected against the influence of temperature according to requirements. The feature of the invention is that elongated parts of textile machines, particularly flat hosiery frames, which on account of their form and nature respond relatively rapidly to ambient temperature fluctuations as regards elongation and contraction, are insulated against temperature influences whereby in the cooperation of said elongated parts and of functional devices carried thereby with other elongated parts and functional devices which respond relatively slowly in their elongation and contraction to ambient temperature fluctuations, is preserved substantially unaltered during periods of warming up and cooling down. It will be understood that when the temperature has become steady after a rise or a drop, both the rapidly responsive parts and the slowly responsive parts will eventually elongate or contract to an equal extent and that the cooperation between them which existed under steady temperature condition before the rise or drop will be unchanged under the different steady temperature condition prevailing after the rise or drop. The insulation of the more rapidly responsive parts thus ensures that this cooperation, even in the case of devices cooperating with each other in very limited ranges longitudinally of the elongated parts, will remain undisturbed during periods of warming up and cooling down. It is obvious that the invention can

be applied in a very simple and cheap way without altering the construction of say the narrowing rods and their adjusting means simply by providing the parts to be insulated with a coating consisting of a poor heat conductor. Insulations of this kind are known already but employed till now for other purposes, such as preventing losses of heat, etc.

By way of example, the invention is illustrated in the accompanying drawing, in which Figure 1 is a front view of the narrowing rod and clock point bar of a flat hosiery frame, only the clock point being fitted with needles for the sake of greater clearness; and Figs 2 and 3 are cross sections on a somewhat enlarged scale of the clock point bar.

Referring to the drawing, the carrier bar 1 for the bearings 4 of the narrowing rods 2 and clock point bars 3 as well as the narrowing rods 2 and clock point bars 3 themselves extend, as a rule, in known manner over the entire length of the machine and are relatively thin, whereby they would elongate and contract relatively rapidly in response to temperature changes. During large variations in temperature the bars 2, 3 will therefore undergo a change in length to such an extent that their covering needles cannot cooperate any more with the frame needles, which are fixed in a more massive part of the machine whereof the length responds more slowly to ambient temperature fluctuations. For this reason, these parts, and particularly the clock point bar 3, are insulated according to the invention against the influences of temperature, the clock point bar 3 being for instance insulated simply by providing it with a coat consisting of a poor heat conductor (Fig. 3) or by covering it with detachable shells 5 made of insulating material, such as wood (Fig. 2), and secured to the clock point bar 3 by means of clips 6 or other suitable means.

In certain textile machines only one set of transfer points are carried by the rapidly responsive parts to variations of temperature, and these points are in alignment with the needles of the machine.

If the shells 5 are firmly connected with the clock point bar 3, their length must be dimensioned so as not to interfere with the axial working motions of the clock point bar 3.

It is of course possible to insulate still other parts of a flat hosiery frame against influences of temperature in order to prevent service troubles due to changes in temperature. The invention can further be applied to other hosiery machines

and to all textile machines subjected to similar conditions as flat hosiery frames.

I claim:—

1. In a textile machine, an elongated element of 5 thin cross section carrying functional devices, said element being movable axially through a limited range, an elongated element of greater cross section carrying functional devices cooperating with the first mentioned functional devices 10 in their limited range of axial movement, and shells of heat insulating material on the element of thin cross section adapted to substantially equalize the elongations and contractions of said elements when they are both exposed to the same 15 temperature fluctuations, said shells being arranged to avoid obstruction of the axial movements of said element of thin cross section.
2. A textile machine, particularly a flat hosiery frame having rapidly and slowly responsive parts 20 to variations of temperature relative to said parts, said rapidly responsive parts carrying transfer points, comprising insulating means on the rapidly responsive parts so that upon exposure to temperature variations the changes in the rapidly 25 responsive parts will be retarded whereby all the parts will expand or contract uniformly to maintain the transfer points in alignment with the needles of the machine, said insulating means being arranged to avoid obstruction to the move-

ments of said rapidly responsive parts while covering an effective area thereof.

3. A textile machine, particularly a flat hosiery frame having rapidly and slowly responsive parts 5 to variations of temperature relative to said parts, said rapidly responsive parts including narrowing rods and clock point bars carrying clock points, comprising insulating means on the rapidly 10 responsive parts so that upon exposure to temperature variations the changes in the rapidly responsive parts will be retarded whereby all the parts will expand or contract uniformly to maintain the clock points in alignment with the needles of the machine, said insulating means being arranged to avoid obstruction to the movements 15 of said rapidly responsive parts while covering an effective area thereof.

4. A textile machine according to claim 3, in 20 which the insulating means is a coating of a poor heat conductor.

5. A textile machine according to claim 3, in 25 which the insulating means comprises a detachable shell of insulating material.

6. A textile machine according to claim 3, in 25 which the insulating means comprises a detachable shell of insulating material and securing clips for the shell.

ARTHUR RICHTER.
